UNITED STATES PATENT OFFICE.

CHARLES A. FISK, OF ABBOTSFORD, QUEBEC, CANADA.

CONTROLLING MEANS FOR GRAMOPHONES.

1,354,961.

Specification of Letters Patent.

Patented Oct. 5, 1920.

Application filed July 1, 1919. Serial No. 307,961.

To all whom it may concern:

Be it known that I, CHARLES A. FISK, a subject of the King of Great Britain, and resident of Abbotsford, in the Province of

Quebec and Dominion of Canada, have invented certain new and useful Improvements in Controlling Means for Gramophones, of which the following is a full, clear, and exact description.

10 This invention relates to improvements in means for controlling or regulating the tone and volume of sound produced by gramophones, and the object of the invention is to provide a simple, inexpensive, durable and 15 easily adjusted means by which the sound produced by a gramophone may be regulated as to tone and volume.

The device consists briefly of a horn which may be built into the casing of a gramophone or otherwise suitably located having 20 separate sounding boxes surrounding it. The tone arm of the gramophone leads into the horn and is provided with an adjustable diaphragm. Various sound regulating 25 means may be mounted in the horn.

In the drawings which illustrate the invention;—

Figure 1 is a vertical, longitudinal, sectional view of the device.

30 Fig. 2 is a front elevation.

Referring more particularly to the drawings, 11 designates the horn of a gramophone which may be located within the casing 12 or otherwise suitably disposed. This 35 horn may, for convenience, be rectangular in cross section as shown in Fig. 2 and is preferably constructed of thin sheets of wood which will vibrate to a limited extent. On each of the four sides of the horn a sound box 13 is provided, constructed of 40 thin sheets of wood or other suitable material. These sound boxes have substantially the same taper as the horn and are arranged with their small ends adjacent the 45 small end of the horn. Both ends of the horn are open, while only the large ends of the sound boxes are open.

The tone arm 14 of the gramophone is connected to a conduit 15 which passes 50 through one of the sound boxes into a slightly flaring mouth-piece 16, located within the horn adjacent the small end thereof. The lower end of this mouth-piece is eccentrically connected to a substantially 55 circularly inclined sounding board 17. The more elevated and longer end of this sound-

ing board is directed toward the large end of the horn while the lowermost portion thereof is adjacent the small end of the horn and located substantially on the longitudinal axis of the horn. Below the sounding board 17 a vibratable diaphragm 18 is provided. This diaphragm is mounted in a trunnioned frame 19 supported by vertically adjustable telescopic posts 20. The upper 60 ends of these posts 20 may, if desired, be mounted in guides 21 so that the diaphragm may be moved toward or away from the mouth of the horn as well as toward or away from the sounding board and angularly about its own axis.

In the small end of the horn a suitably shaped reflector 22 is adjustably mounted so that it may be moved toward or away from the large end of the horn.

A suitable distance in front of the sounding board 17 and diaphragm 18 a plurality of diaphragms 23 may be mounted in the horn. The lowermost of these diaphragms is preferably the largest in diameter and the uppermost diaphragm the smallest in diameter, the intermediate diaphragms being of intermediate sizes. These diaphragms may be mounted by means of small studs 24 or the like, so as to be spaced away from the 85 horn.

The operation of the device is extremely simple. Sound waves pass from the tone arm through the conduit 15 and mouth-piece 16 onto the diaphragm 18 from which they 90 are deflected to the sounding board 17. From the sounding board the waves are deflected either to the lowermost diaphragm 23 or to the bottom wall of the horn or both. The waves are then deflected back and forth 95 between the top and bottom of the horn until they escape at the large end thereof. This deflection back and forth of the sound waves produces amplification of the sound. In addition there is further amplification 100 caused by vibration of the horn walls setting up vibrations in the sound boxes 13. The waves emerging from the sound boxes mingle and blend with the waves emerging from the horn producing a much mellower 105 and more pleasing tone than that produced by the ordinary horn. The volume of sound and tone are regulated by means of the diaphragm 18 which can be raised or lowered, moved backward or forward, or rocked 110 about its trunnions so as to regulate the number and frequency of deflections within

the horn. The diaphragm may be moved up until it lies against the sounding board, with the result that the sound is so muffled as to be almost inaudible. Between this full closed and the full open position there is an infinite variety of adjustments possible giving any desired regulation of tone and volume. Normally, the diaphragm may be set to deflect sound waves toward the mouth of the horn but if desired it may be made to deflect the sound waves toward the deflector 22. In ordinary use the reflector serves to throw the sound waves forwardly to the mouth of the horn in much the same manner that light is projected by a condensing reflector. Ordinarily, the tone is regulated by the distance between the diaphragm 18 and sounding board 17 and the volume by the inclination of the diaphragm but it will be understood that each adjustment effects, to a certain extent, both tone and volume.

It has been discovered that, by means of this apparatus, a gramophone may, as it were, be tuned to the room in which it is to be used, thus producing the desired result to the maximum degree in all circumstances. The forward and rearward adjustment of the diaphragm will assist greatly in this tuning of the machine to the room.

Having thus described my invention, what I claim is:—

- 35 1. In a device of the class described, a horn, a sound conduit opening into the side of the horn, a flaring mouth-piece on said conduit within the horn, a sounding board carried by said mouth-piece and a diaphragm below the sounding board.
- 40 2. A device according to claim 1, in which the sounding board is arranged eccentrically with respect to the mouth-piece.
- 45 3. A device according to claim 1, in which the sounding board is inclined with respect to the axis of the horn.
- 45 4. A device according to claim 1, in which the sounding board is arranged eccentrically

with respect to the mouth-piece and is inclined with respect to the axes of the horn and mouth-piece, the sounding board being more remote from the horn axis at the large end than at the small end.

5 5. A device according to claim 1, in which the diaphragm is adjustably mounted.

6 6. A device according to claim 1, in which the diaphragm is adapted to oscillate about a diameter thereof normal to the horn axis.

7 7. A device according to claim 1, in which the diaphragm is mounted for adjustment toward and away from the sounding board and toward and away from the mouth of the horn.

8 8. A device according to claim 1, in which the diaphragm is positioned to deflect sound waves emerging from the mouth-piece onto the sounding board.

9 9. In a device of the class described, a horn having a series of diaphragms spaced around the inner wall thereof.

10 10. In a device of the class described, a horn, a conduit opening into one side of the horn, a sounding board carried by the conduit within the horn, a diaphragm in the path of the conduit opposing said sounding board, and a series of additional diaphragms spaced around the inner wall of the horn between the forward end thereof and said first mentioned diaphragm.

11 11. In a device of the class described, a horn having a reflector adjustably mounted in the rear end thereof.

12 12. In a device of the class described, a horn, a conduit extending into the horn from one side, a diaphragm mounted adjacent the inner end of the conduit and within the horn, and a reflector at the rear end of the horn adapted to coöperate with said diaphragm in deflecting the sound waves toward the forward end of the horn.

In witness whereof, I have hereunto set my hand.

CHARLES A. FISK.
